DESIGN FOR A TEXTILE FABRIC

Jack P. Gold, Woodmere, N. Y.

Application March 11, 1936, Serial No. 61,562

Term of patent 3½ years

To all whom it may concern:

Be it known that I, Jack P. Gold, a citizen of the United States of America, residing in Woodmere, Long Island, county of Nassau, and State of New York, have invented a new, original, and ornamental Design for a Textile Fabric, of which the following is a specification, reference being had to the accompanying drawing, forming part thereof.

The figure in the drawing is a plan view of a textile fabric showing my new design.

The solid black portion represents a solid colored stripe which is continued throughout the fabric.

I claim:

The ornamental design for a textile fabric substantially as shown and described.

JACK P. GOLD.
